APPARATUS FOR APPLYING TIPPING TO
PROPELLER BLADESAlbert H. Lambert, Dayton, and Ira R. Barr,
Yellow Springs, Ohio

Application December 11, 1946, Serial No. 715,598

4 Claims. (Cl. 154—1.6)

(Granted under the act of March 3, 1883, as
amended April 30, 1928; 370 O. G. 757)

1

The invention described herein may be manufactured and used by or for the Government for governmental purposes without payment to us of any royalty thereon.

This invention relates to an apparatus and a method for applying tipping to the leading edge of a propeller blade.

One of the essential objects of this invention is to provide a novel apparatus whereby the metal tipping, which is usually a thin sheet of stainless steel, can be quickly and securely applied onto the leading edge of a propeller blade of wood, metal, plastic or the like, and without employing any rivet holes or rivets or screws.

A more particular object of this invention is to provide a novel apparatus or tipping jig whereby the tipping can be readily applied to the propeller blade by employing a suitable adhesive and pressure, thereby actually strengthening the blade, and thus obviating the customary practice of drilling holes in the blade and in the tipping and inserting rivets or screws therein, which former practice weakened the blade and the tipping and also required much additional time and labor.

Another object of this invention is to provide such an apparatus for securing tipping onto the edge of a propeller blade by means of adhesive and pressure wherein pliable tubular means is utilized to bear upon the outer surface of the tipping and is operable by pneumatic pressure, so as to apply the pressure uniformly over the entire tipping surface and secure the tipping throughout its entire area with uniform firmness onto the edge of the blade.

Another object of this invention is to provide a novel method of applying tipping on the edge of a propeller blade by the use of adhesive applied with pressure, or with heat and pressure, so as to make such application considerably easier and speedier and thus less expensive, and also rendering a sturdier construction, than was accomplished by the former procedure of drilling holes in the blade and in the tipping and then inserting rivets or screws therein.

A further object of this invention is to provide a novel method of securing tipping onto a propeller blade whereby regulated heat as well as constant high pressure is applied in the process for a certain length of time, so that a hot-setting adhesive as well as a cold-setting adhesive may be used in binding the tipping onto the edge of the blade.

These and various other objects and advantages are attained with this invention, as will become apparent from the following description, taken in connection with the accompanying drawing wherein the invention is shown in its preferred form, it being evident that other arrangements and forms of construction may be

2

resorted to in carrying out the objects and purposes of this invention.

In the drawings:

Fig. 1 is a side elevational view of the apparatus, parts being broken away.

Fig. 2 is an end elevational view thereof, with the hub support shown in section.

Fig. 3 is a vertical sectional view, taken on line 3—3 of Fig. 1.

Fig. 4 is a plan view, with parts broken away.

Fig. 5 is an enlarged fragmentary section, taken across the pressure hose together with the insulating layer and glass fiber layer thereon, pressing the tipping with the adhesive onto the propeller blade.

This apparatus briefly comprises a supporting frame 11 which in this disclosed form of construction includes a base 12 carrying thereon means 13 for supporting one edge part of the propeller blade 14, and means 15 for supporting the hub part 16 of the blade; and also includes holding means 17 for holding the tipping 18 in place upon the opposite edge part of the blade and which preferably includes means 19 for applying pressure or heat and pressure for a certain length of time to the tipping, so as to secure it evenly and firmly by the interposed adhesive means onto the blade edge.

The base 12 of the frame 11 includes two supporting beams 21 extending longitudinally of the frame 11, and held together by several base planks 22 secured thereunder.

The blade supporting means 13 includes a set of supporting beams 23 secured upon said beam

35 21, crosswise of the frame; and blade supporting members 24 mounted adjustably upon said beams 23, as by companion groove and tongue means 23' and 24' provided on said beams 23 and on said members 24, and by use of clamping ele-

40 ments 25 in the form of looped rods, each having its upper curved part engaging in a notch 26 provided on the top shoulder of a member 24, and having the lower curved part surrounding a beam 23. A wedge 27 is driven between the bottom of a

45 beam 23 and of a rod 25, to force and retain the member 24 tightly onto the beam 23. These beams 23 are arranged in pairs and each pair of beams has the adjoining faces 28 slanting to provide a trough therebetween, so as to fit the contour of the propeller blade 14, while a layer or

50 lining 29 of pliable material, for instance felt or wool, is secured on each face 28 and has sufficient creep to adjust itself snugly to the contour of the blade. Said members 24 are thus adjustable 55 along said tongue and groove means on beams 23, to accommodate propeller blades of different sizes.

The means 15 for supporting the hub part 16 of the blade comprises a footing bar 31 secured upon the beams 21 at one end of the frame and carry-

ing a lower hub supporting bracket 32 thereon, which is preferably made of metal in the form of a disc fixed on bar 31 and having an arm 33 arising therefrom. Said means 15 also comprises hub clamping means which is mounted on arm 33, and this means includes a lower hub plate 34, preferably a metal disc, having a pair of arms 35 integral thereon and depending therefrom and provided with a slot 36 for receiving a bolt 37 which extends through arm 33, to allow for adjustment of the arm 35 with disc 34 on the fixed bracket 32. An upper hub disc 41 of metal has a neck 42 thereon, and a bolt 43 extends through said neck and through a central aperture in disc 34 and through a bushing 44 positioned between said discs, while a pair of circular wood plates 45 are placed between the ends of said bushing 44 and of said discs 34 and 41 to engage and clamp the two side faces of the hub portion 16, by the tightening of either the upper or the lower nut 46 or 47 on said bolt 43. A slot 48 in the two arms 35 receive and hold the lower nut 47 from turning while upper nut 46 is being applied on the bolt. This bolt has excess length to accommodate blade hubs of different sizes.

The means 15 herein supports the hub portion 16 of the propeller, while the trailing edge part of the blade 14 is supported in the set of troughs formed between the several pairs of pliable layers 29 on the pairs of slanting faces 28 of members 24.

This supporting means 15 as disclosed is adapted best for supporting a fixed pitch propeller, but it is apparent that a detachable propeller blade may be similarly supported hereby.

In this form of apparatus disclosed herein the upper holding means 17 is shown mounted over the leading edge of the propeller blade, wherein the tipping 18 is being applied, and is provided with special pressure applying means 19 to bear upon the outer side of said tipping and force it onto the blade edge. Herein the means 17 includes a holding member which is in the shape of a beam 51 extending over the edge of the blade and over the tipping thereon, longitudinally of the frame 11, and has the means 19 interposed between it and the tipping 18. The beam 51 is hingedly mounted on the frame and is movable upwardly from the supporting means 13, to facilitate mounting the propeller blade and the tipping thereon. Said holding beam 51 has a set of hinge bars 52 extending crosswise thereof and secured thereon by bolts 53. Hinge elements 54 are provided, each preferably consisting of a looped rod having its upper part resting in a notch 55 provided on the top of one of the bars 52 with a cover plate 56 secured thereover; while the lower curved part of each looped rod 54 is separated and the two ends 54' are engaged in apertures at opposite sides of one of the beams 23, thus affording a swinging movement or hinging effect to the bars 52 with beam 51, upwardly from the position shown.

Hinge elements 57, in the form of looped rods, have each the lower part separated and the two ends 57' snapped into a pair of apertures on the opposite sides of a beam 23, at the end opposite hinge element 54 thereon. The upper yoke part of each hinge element 57 is mounted off center in an eccentric 58 which is seated on the end part of a cross-bar 52, opposite plate 56; and a handle 59 on said eccentric facilitates swinging it into clamping position, as shown in full lines in Fig. 3, or into release position, as shown in dotted lines therein. Two washers 60 are posi-

tioned at the opposite sides of each eccentric 58 and welded to the hinge rod 57, to retain the eccentric against sidewise movement.

The pressure applying means 19 is associated with the holding beam 17, and preferably consists of a pliable tubular member 61 expandible by pneumatic pressure, and in this form of construction as disclosed herein a fire hose is conveniently and economically utilized which is mounted in an arched groove 62 provided in the nether face of beam 51. Said hose is of a size to extend over the full length of the blade 14 and of the tipping 18 and so as to cover substantially the entire outer surface of the tipping, about as indicated in Fig. 3, wherein the hose is shown deflated. Suitable pressure inlet means 63 on the hose 61 admits a pressure medium into the hose, such as compressed air, stream, or other expandible fluid that may be placed under heavy pressure.

In cases where it is desired to apply heat along with the pressure, to secure the tipping on the blade, as by the use of hot-setting adhesive, hot steam can be used instead of cold air as the pressure medium in tubular member 61. However, said pressure applying means 19 is herein shown as furthermore provided with a special heating means 65 adapted to be used for heating the tipping and the adhesive material whenever that is desirable. This means 65 is shown herein as comprising an electric heating coil 66, an Omaloy resistance heater being suitable with current supplied through an electric conductor 67, and having an insulating layer 68 of asbestos placed between the heater and the hose, and a layer 69 of fiber glass cloth placed inward of the heating coil and adjoining the tipping 18, so as to heat said tipping and the adhesive 70 that was applied as coatings or linings on the two joinable parts of the blade 14 and the tipping 18, as best shown in Fig. 5.

In the procedure of tipping a propeller blade by the use of this apparatus, the edge part of the blade 14, whether of metal or wood or other material, is sanded on the surface to be covered by the tipping, parallel to the line of gyration, to roughen the same for providing a stronger bond.

The tipping is preformed in harmony with the surface of the blade edge, and its inside surface is preferably roughened, care being taken that rust or oxide or scales are removed therefrom as well as any grease or dust.

The propeller is then placed on the support and has its hub portion 16 secured in the hub clamping means 15, and is brought into position so that the blade 14 rests within the set of troughs provided by the pairs of slanting face portions 28 with linings 29 on the supporting members 24, as best seen in Fig. 3.

The adhesive material 70 used may be either cold-setting adhesive or hot-setting adhesive. By the use of the cold-setting adhesive a film of the cement is provided between the tipping and the blade edge, being preferably applied in the form of a thin film to the joinable surfaces of both the tipping and the blade edge, and allowed to dry for about 15 minutes or until the film thereof becomes tacky. Said cement may be Casco Flexible cement, a dilutable water-dispersion of casein and synthetic rubber latex in liquid form. The tipping is then applied in its proper position on the blade edge, and the pressure applying means 19 as well as the holding means 17 are then brought into holding position 75 upon the entire outer surface of the tipping, and

the eccentric 58 is locked in position. The pressure medium is then applied to the hose to inflate it to substantially a pressure of approximately 100 p. s. i., thereby pressing the entire tipping with the adhesive thereon firmly and uniformly onto the edge of the blade. The apparatus and the tipping is thus left under the pressure for approximately 48 hours. No heating means is required with this cold-setting procedure.

With the use of hot-setting adhesive, a thermosetting synthetic resin is preferably used, for which the substance known as "Redux" is suitable. The adhesive is provided between the tipping and the blade edge, and a thin film of the adhesive is preferably applied to both of the joinable portions of the tipping and of the blade; while a resistance heater with its electric connections, being provided with the layer of glass cloth insulation thereunder and with the layer of asbestos insulation thereover, is placed on the tipping for the entire length thereof, and the hose 61 is applied thereover, whereupon the holding means is secured in position. The heater may also be connected to the hose and applied together therewith. The pneumatic pressure is applied to the hose, approximately 100 p. s. i., and the electric current is applied to the heater to raise the temperature at the line of the adhesive to approximately 300° F., measured with a thermocouple. This temperature is developed in about 3 minutes, and said temperature is then maintained for about 10 minutes when the current is cut off. About 13 minutes elapses for said temperature to drop to a normal degree, and the blade together with the tipping which is very firmly and evenly secured thereon may then be removed from the apparatus.

This apparatus and these methods of applying the metal tipping to either a wood or a metal propeller blade, by the use of adhesive and pressure, have provided excellent results as proven by various whirl tests and engine tests conducted therewith. These tests have disclosed the production of a more even and secure bond between the tipping and the blade edge, by the use of this method and apparatus, than had been accomplished heretofore with the customary procedure of providing rivet holes in both the tipping and the blade and then securing rivets or screws therein, and a stronger blade and tipping are hereby produced, due to the absence of rivet holes in the tipping and in the blade.

By the use of this apparatus and method, stainless steel tipping can now be applied efficiently and securely to aluminum alloy propellers, as well as to other metal, wood or plastic propellers.

Our tipping jig is adapted for use with either fixed pitch or detachable blade propellers, and for different models.

The pivot action of the hub supporting means will enable proper positioning of any type blade of a fixed pitch propeller.

This apparatus can be quickly set up and speedily used in tipping a blade, thus saving time and labor and effecting economy, and it is also portable to facilitate its use.

We claim:

1. An apparatus for applying tipping to a propeller blade with adhesive between their adjoining parts, said apparatus comprising a supporting frame, means on the frame for embracing and

supporting the hub part of the propeller and being adjustable angularly about the blade axis to suit different forms of propellers and different degrees of blade twist, means longitudinally spaced on the frame for embracing the trailing edge part of the blade and being adjustable transversely on the frame to accommodate blades of different sizes and shapes, and means in the form of an inverted trough positioned over the leading edge of the blade and including expansible means for engaging the tipping to press it with the adhesive firmly and evenly onto the edge of the blade.

2. An apparatus for applying tipping to a propeller blade while both the tipping and the blade edge have adhesive provided on their adjoining parts, said apparatus comprising a supporting frame, means thereon for supporting and securing the hub part of the propeller and being adjustable angularly about the blade axis for accommodating propellers of different types and different degrees of blade twist, means longitudinally spaced on the frame for supporting the trailing part of the blade and being adjustable transversely of the frame to accommodate blades of different sizes and shape, holding means hingedly mounted above the blade supporting means and including means for securing the holding means in position over the blade, and tubular means retained in position by said holding means to extend over the entire outer surface of the tipping and being expansible by pneumatic pressure for forcing the tipping with its adhesive firmly and evenly onto said leading edge of the blade.

3. The subject matter set forth in claim 2, and wherein heating means is provided to overlie the tipping for heating it and said adhesive.

4. An apparatus for applying tipping to a propeller blade, where a lining of adhesive is provided between the adjoining parts of the tipping and the blade, said apparatus comprising a supporting frame, means thereon embracing the hub part of the propeller and being angularly adjustable about the blade axis for accommodating blades of different sizes and twist, means longitudinally spaced apart on the frame including cushioned trough-shaped means for supporting the trailing part of the blade and being transversely adjustable to accommodate blades of different sizes and shapes, holding means hingedly mounted on the blade supporting means above said blade supporting means and including a beam and means for securing it in position over the blade, and a pliable tube retained in position by a groove in the underside of said beam for engaging the entire outer surface of the tipping and being expansible by pneumatic pressure for forcing the tipping with its adhesive firmly and evenly onto said leading edge of the blade.

ALBERT H. LAMBERT.
